UNITED STATES PATENT OFFICE.

LEWIS T. RHOADES, OF PHOENIXVILLE, PENNSYLVANIA, ASSIGNOR TO
MARIE V. GEHRING, OF PHILADELPHIA, PENNSYLVANIA.

WAVE-DETECTOR.

SPECIFICATION forming part of Letters Patent No. 711,123, dated October 14, 1902.

Application filed August 29, 1902. Serial No. 121,439. (No model.)

To all whom it may concern:

Be it known that I, LEWIS T. RHOADES, a citizen of the United States, residing at Phoenixville, in the county of Chester and State of Pennsylvania, have invented a new and useful 5 Wave-Detector, of which the following is a specification.

My invention relates to wireless-signaling systems in which messages are transmitted to 10 the natural media in the form of electroradiant energy and which are recorded at the receiving-station through the agency of a detector of electroradiant energy, which then controls a local recording-circuit.

15 More particularly, my invention relates to a device for manifesting the presence of electroradiant energy and which is extremely sensitive, reliable, and not easily rendered useless.

20 My invention comprises a wave-detecting device which changes its resistance under the influence of electromagnetic radiations and immediately restores itself to its normal condition upon the cessation of the radiations.

25 My invention comprises a material for wave-detectors having the aforementioned properties and is in its finished state in the nature of a paste. In compounding this paste or material for the wave-detecting device I employ 30 mild steel in the form of very fine particles and also French carbon which has been reduced to very fine granules. To equal portions of the mild steel and carbon I add twenty per cent. nickel, also in a fine state, and these 35 ingredients are mixed with enough vaseline to make the whole mass a thick paste. This paste is then placed between metallic terminals, which are then included in the circuit of the receivers of wireless-signaling systems 40 in the well-known relations.

Referring to the drawings, Figure 1 is a sectional view of the wave-detector. Fig. 2 is the sectional view of a modified form.

T represents a cylindrical tube or envelop 45 of insulating material, preferably glass, within which are the metallic terminals M M, which are preferably of silver or platinum.

A represents the plastic and paste-like material above described.

50 P P are plugs in the ends of the tube T, and

through them extend the connecting-wires W W', by means of which the wave-detector is connected in the usual manner in the receiving-circuits of wireless-signaling systems.

Fig. 2 is the same as Fig. 1, with the exception that between the metallic terminals M M and separated from them is a third metallic disk M', preferably of the same material as the terminals M M. This arrangement affords two spaces, in which are placed masses 60 of the wave-detecting paste A A, whose composition has been described above.

In actual practice the dimensions of the wave-detector are many times smaller than those shown on the accompanying drawings. 65

I find that a mixture of mild steel and carbon with vaseline will operate as previously described, and that also a mixture of nickel, carbon, and vaseline will operate likewise; but my preferred composition contains the 70 mild steel, carbon, nickel, and vaseline. In place of vaseline may be used any other hydrocarbon having the thick constituency of vaseline, or, in fact, any material which is an insulator like vaseline and which has a similar constituency. Furthermore, in place of vaseline may be used numerous other materials for the purpose of supporting the metal and carbon particles in a mass resembling 75 paste. The carbon I use is either amorphous or graphitic.

The wave-responsive device or wave-detector herein described has the property of self-restoration—that is, upon the cessation of the electroradiant energy it returns automatically to its normal condition and does not require mechanical shock. 85

What I claim is—

1. A material for a wave-responsive device comprising nickel and carbon. 90
2. As a material for a wave-responsive device, a mixture of nickel and carbon.
3. A material for a wave-responsive device, comprising finely-divided nickel with carbon.
4. A material for a wave-responsive device 95 comprising a mixture of nickel with finely-divided carbon.
5. A material for a wave-responsive device, comprising a mixture of carbon and nickel both finely divided. 100

6. A material for a wave-responsive device comprising a mixture of nickel and carbon in a material serving as a paste. 70
7. A material for a wave-responsive device comprising a mixture of nickel, carbon and a hydrocarbon. 75
8. A material for a wave-responsive device comprising a mixture of carbon and nickel, both finely divided, and a hydrocarbon serving as a supporting medium therefor. 75
9. A material for a wave-responsive device comprising a mixture of nickel, carbon and vaseline. 80
10. A material for a wave-responsive device, consisting of a mixture containing nickel and carbon, both finely divided, and vaseline serving as a supporting medium therefor. 85
11. A material for a wave-responsive device, comprising a mixture of iron, carbon and a hydrocarbon. 90
12. A material for a wave-responsive device, comprising iron, finely divided, carbon and a hydrocarbon. 95
13. A material for a wave-responsive device comprising iron, finely-divided carbon and a hydrocarbon. 100
14. A material for a wave-responsive device, comprising iron and carbon, both finely divided and a hydrocarbon. 105
15. A material for a wave-responsive device, comprising iron, carbon and vaseline. 110
16. A material for a wave-responsive device, comprising iron, finely divided, carbon and vaseline. 115
17. A material for a wave-responsive device, comprising iron, finely-divided carbon and vaseline. 120
18. A material for a wave-responsive device, comprising iron and carbon, both finely divided, and vaseline. 125
19. A material for a wave-responsive device, comprising iron, nickel and carbon. 130
20. A material for a wave-responsive device, comprising iron, nickel and carbon, all finely divided. 135
21. A material for a wave-responsive device, consisting of iron, nickel and carbon, and a supporting medium therefor. 140
22. A material for a wave-responsive device, consisting of iron, nickel and carbon, all finely divided, and a supporting medium therefor. 145
23. A material for a wave-responsive device, consisting of iron, nickel, carbon, and an insulating medium as a support therefor. 150
24. A material for a wave-responsive device, consisting of iron, nickel, carbon, all finely divided, and an insulating medium forming a plastic mass therewith. 155
25. A material for a wave-responsive device, consisting of iron, nickel, carbon, and a hydrocarbon supporting medium therefor. 160
26. A material for a wave-responsive device, consisting of iron, nickel and carbon, all finely divided, and a hydrocarbon serving as a supporting medium therefor. 165
27. A material for a wave-responsive de- vice, consisting of iron, nickel and carbon, all finely divided, and an insulating medium of hydrocarbon as a support therefor. 170
28. A material for a wave-responsive device, consisting of iron, nickel and carbon, all finely divided, and an insulating medium of hydrocarbon forming a paste therewith. 175
29. A material for a wave-responsive de- vice, consisting of iron, nickel, carbon, and vaseline. 180
30. A material for a wave-responsive de- vice consisting of iron, nickel, carbon, all finely divided, and vaseline. 185
31. A material for a wave-responsive de- vice, consisting of iron, nickel and carbon, and a supporting medium therefor consisting of vaseline. 190
32. A material for a wave-responsive de- vice, consisting of iron, nickel and carbon, all finely divided, and a supporting medium therefor consisting of vaseline. 195
33. A material for a wave-responsive de- vice, consisting of iron, nickel, carbon, and an insulating medium as a support therefor consisting of vaseline. 200
34. A material for a wave-responsive de- vice, consisting of iron, nickel, carbon, all finely divided, and an insulating medium of vaseline forming a plastic mass therewith. 205
35. A material for a wave-responsive de- vice, comprising a paste composed of nickel, carbon, and an insulating medium. 210
36. A material for a wave-responsive de- vice, comprising a paste composed of nickel and carbon, and a medium of hydrocarbon. 215
37. A material for a wave-responsive de- vice, comprising a paste composed of nickel, carbon and vaseline. 220
38. A material for a wave-responsive de- vice, comprising a paste composed of iron, and carbon, and an insulating medium. 225
39. A material for a wave-responsive de- vice, comprising a paste composed of iron and carbon, and an insulating medium of hydro- carbon. 230
40. A material for a wave-responsive de- vice, comprising a paste composed of iron, car- bon, and vaseline. 235
41. A material for a wave-responsive de- vice, comprising iron, carbon, both finely di- vided, and vaseline. 240
42. A material for a wave-responsive de- vice, comprising iron, nickel, both finely di- vided, in a paste of hydrocarbon. 245
43. A material for a wave-responsive de- vice, comprising a paste composed of iron, nickel, both finely divided, and vaseline. 250
44. A material for a wave-responsive de- vice, consisting of a paste composed of iron, nickel, carbon, and a hydrocarbon. 255
45. A material for a wave-responsive de- vice, consisting of a paste composed of iron, nickel, carbon, and an insulating material. 260
46. A material for a wave-responsive de- vice, consisting of a paste composed of iron, nickel, carbon, and vaseline. 265
47. A material for a wave-responsive de-

- vice, comprising a paste composed of mild steel, carbon, and a hydrocarbon.
48. A material for a wave-responsive device, comprising a paste composed of mild steel, carbon, and vaseline.
49. A material for a wave-responsive device, comprising a paste composed of mild steel, carbon, and a binder.
50. A material for a wave-responsive device, comprising a paste composed of mild steel, carbon, and a hydrocarbon binder.
51. A material for a wave-responsive device, consisting of a paste composed of mild steel, nickel, carbon, and a binder.
52. A material for a wave-responsive device, consisting of a paste composed of mild steel, nickel, carbon, and a hydrocarbon binder.
53. A material for a wave-responsive device, consisting of a paste composed of mild steel, nickel, carbon and vaseline.
54. A material for a wave-responsive device comprising a paste composed of mild steel, and graphite with a binder.
55. A material for a wave-responsive device, consisting of a paste composed of mild steel, graphite, and a hydrocarbon binder.
56. A material for a wave-responsive device, consisting of a paste composed of mild steel, graphite and vaseline.
57. A material for a wave-responsive device, consisting of a paste composed of mild steel, nickel, graphite, and a binder.
58. A material for a wave-responsive device, consisting of a paste composed of mild steel, nickel, graphite, and a hydrocarbon binder.
59. A material for a wave-responsive device, consisting of a paste composed of mild steel, nickel, graphite, and vaseline.
60. A wave-responsive device comprising metallic terminals bridged by a mixture containing nickel and carbon.
61. A wave-responsive device comprising metallic terminals bridged by a mixture containing nickel, carbon, and a binder.
62. A wave-responsive device comprising metallic terminals bridged by a mixture containing iron, nickel, and carbon.
63. A wave-responsive device comprising metallic terminals bridged by a mixture of iron, nickel, carbon, and a hydrocarbon.
64. A wave-responsive device comprising metallic terminals bridged by a mixture of iron, nickel, carbon and vaseline.
65. A wave-responsive device comprising metallic terminals bridged by a paste composed of iron, nickel and carbon and a binder.
66. A wave-responsive device comprising metallic terminals bridged by a paste composed of iron, nickel, carbon and vaseline.
67. A wave-responsive device comprising metallic terminals bridged by a paste composed of mild steel, carbon and a binder.
68. A wave-responsive device comprising 65 metallic terminals bridged by a paste composed of mild steel, carbon, and hydrocarbon.
69. A wave-responsive device comprising metallic terminals bridged by a paste composed of mild steel, carbon and vaseline. 70
70. A wave-responsive device comprising metallic terminals bridged by a paste composed of mild steel, nickel, carbon, and a hydrocarbon.
71. A wave-responsive device comprising 75 metallic terminals bridged by a paste composed of mild steel, nickel, carbon, and vaseline.
72. A wave-responsive device comprising 80 metallic terminals bridged by a paste composed of mild steel, nickel, graphite and vaseline.
73. A wave-responsive device comprising metallic terminals bridged by a paste composed of mild steel, graphite and a hydrocarbon binder. 85
74. A wave-responsive device comprising metallic terminals bridged by a paste composed of mild steel, graphite and vaseline.
75. A wave-responsive device comprising 90 metallic terminals bridged by a paste composed of nickel, graphite and vaseline.
76. A wave-responsive device comprising silver terminals bridged by a paste composed of mild steel, nickel, carbon, and vaseline. 95
77. A wave-responsive device comprising silver terminals bridged by a paste composed of mild steel, nickel, carbon, and a hydrocarbon binder.
78. A wave-responsive device comprising 100 metallic terminals, an envelop, and a paste composed of mild steel, nickel, carbon, and vaseline, confined between said terminals and envelop.
79. A wave-responsive device comprising a 105 series of separated metallic masses, and a paste composed of mild steel, nickel, carbon, and vaseline in the spaces between said metallic masses.
80. A wave-responsive device comprising 110 separated metallic masses, an envelop, and in the spaces between said metallic masses and envelop a paste composed of mild steel, nickel, carbon, and vaseline.
81. A wave-responsive device comprising a 115 series of separated masses of silver, the end masses serving as terminals of the device, and in the spaces between said masses a paste composed of mild steel, nickel, carbon, and vaseline. 120
82. A self-recovering wave-responsive device comprising metal terminals and a mixture of steel, carbon and vaseline located between said terminals.

LEWIS T. RHOADES.
